(57) **CLAIM**

The ornamental design for a power module device containing semiconductor elements, as shown and described.

DESCRIPTION

1. Power module device containing semiconductor elements
1.1 : Front
1.2 : Back
1.3 : Top
1.4 : Bottom
1.5 : Right
1.6 : Left
1.7 : Perspective

The broken lines showing portions of the power module device containing semiconductor elements form no part of the claim.

This article is a power module device containing semiconductor elements; this product is used to control and/or supply electric power.
